SOUND TRANSLATING APPARATUS

Stuart Ballantine, Mountain Lakes, N. J.

Application February 12, 1935, Serial No. 6,245

14 Claims. (Cl. 179—1)

This invention relates to sound translating apparatus and particularly to sound translating apparatus adapted for incorporation in an electrical communication system.

The ordinary types of microphones, designed to be actuated by aerial sound waves, must be supported in front of, and preferably close to, the mouth. There are many applications and uses for microphones, however, where this is quite inconvenient even in those cases where some means of support, other than the hands, are provided. Examples of such use are in gas and oxygen masks. According to this invention, I abandon the method of picking up the sound from the air and instead pick up the sound as it exists in the vibration of the upper parts of the body which are set up by the acoustical and mechanical actions of the voice. These vibrations are particularly strong in the region of the larynx and associated cartilaginous structures such as the thyroid cartilage. Devices embodying the invention include apparatus that is applied to the vibrating parts so as to be directly actuated by the mechanical vibrations thereof and acoustical transmission through the air plays a minor role.

Throat microphones have been proposed but, so far as I know, none of the prior devices has been successful in yielding an electrical output which was a faithful replica of the natural sound of the voice. The sound reproduced by the prior devices was composed largely of low frequency components and was muffled, deep and booming, being so highly unintelligible as to be totally unfit for electrical communication purposes.

I have made an experimental study, by wave analysis, of the mechanical vibration amplitudes of the larynx at different frequencies and have found the reason for the failure of the prior devices. I have found that the vibration amplitudes of the larynx diminish very rapidly as the frequency increases and, consequently, the prior art devices did not yield intelligible sounds, for the devices were designed simply to reproduce the vibrations as they exist with total disregard of their spectral distribution.

This frequency distribution of the vibratory energy is reconcilable with the fact that many of the sounds of speech, involving high frequency constituents, are formed in the upper cavities by the lips and tongue and probably reach the larynx, much attenuated, by a backward acoustical transmission which may be more aerial than mechanical. It is well established that these higher frequency components are nec-

essary for intelligible transmission in a telephone circuit, since these are the principal constituents of the majority of consonants.

I have discovered that the higher speech frequencies are represented, in appreciable magnitudes, in the vibratory energy available at the larynx, and that the frequency-vibration amplitude characteristic is such that a high degree of naturalness in the reproduced sound may be obtained by restoring the balance in the frequency distribution of energy. Broadly speaking, this is accomplished by designing the pickup device and its associated apparatus to be much more efficient at high frequencies than at low frequencies, or in other words, to have a rising frequency response characteristic.

Objects of the invention are to provide novel methods and apparatus for converting into electrical currents, for transmission over an electrical system, the acoustical vibrations of certain parts of the body. Objects are to provide methods of and apparatus for producing electrical currents from mechanical vibrations of the throat, the electrical currents being such that, when converted back to sound, the sound reproduction will closely resemble the original voice of the person as heard in the ordinary way or as picked up by a microphone of conventional type designed for aerial sound waves.

A further object is to provide apparatus for use in an electrical communication system, the apparatus being designed for actuation by mechanical vibrations of the throat and being capable of producing electrical currents which are comparable with the currents produced by a good microphone when favorably positioned for actuation by the voice or sound waves in air. More particularly, an object is to provide a mechano-electrical transducer adapted to be placed in contact with and actuated by the mechanical vibrations of the body and a transmission network cooperating with the transducer to deliver electrical waves which, when impressed upon a telephone line or other electrical communication system, result in a reproduction of sound that has the acoustical quality of the voice.

These and other objects and advantages of the invention will be apparent from the following specification when taken with the accompanying drawings, in which:

Fig. 1 is a curve sheet showing a frequency-response characteristic which will yield highly articulated speech from the mechanical vibrations of the larynx;

Fig. 2 is a circuit diagram of a sound reproducing system which embodies the invention;

Fig. 3 is a curve sheet showing the frequency response characteristics of the Fig. 2 apparatus;

Fig. 4 is a fragmentary circuit diagram of another embodiment of the invention;

Fig. 5 is a curve sheet showing the frequency response characteristics of the microphone and of the complete system of Fig. 4; and

Fig. 6 is a fragmentary circuit diagram illustrating a modification of the Fig. 4 circuit.

I have determined, from my studies of the relation between frequency and the vibration amplitudes of the larynx, that there is a general progressive decrease in amplitude towards the higher end of the useful voice frequencies of from 200 to about 4,000 cycles and have determined empirically a frequency response characteristic which may be employed with satisfactory results to correct for the non-uniform energy input at different frequencies. The frequency response characteristic of the apparatus can be described, for explanation of this invention and for engineering purposes, by means of a curve showing the output voltage of the system when the microphone is vibrated mechanically by a piston which is driven sinusoidally at constant velocity at all frequencies. The term "constant velocity" means that the maximum value of the velocity (which varies sinusoidally) is maintained constant. This method of defining the frequency characteristic has been adopted in view of the difficulty of actuating the microphone over the entire frequency range for measurement purposes when it is worn on the throat. The mechanically driven piston is used merely as a convenient way of imparting a definite and reproducible actuation to the microphone.

The frequency response or transmission characteristic shown by curve A of Fig. 1 has been found, experimentally, to yield highly articulated speech from the mechanical vibration of the larynx. The ordinates represent the electrical voltage output while the abscissae indicate the corresponding frequencies at which the microphone was vibrated, as explained above, by a constant velocity piston. To obtain this constant velocity, the amplitude of vibration varied inversely as the frequency. As shown by the dotted line A', the output of the pickup system varies as the 1.3 power of the frequency over the greater part of the curve A. It will be seen from this curve that a considerable readjustment of the relation between high and low frequencies is required to compensate for the frequency distribution in the larynx. It must be understood, of course, that the shape and slope of the curve is not critical, but may be varied somewhat from that shown in Fig. 1. The diagram is intended to show the order of the effect and to indicate why a device of conventional design (for uniform response at all frequencies) is doomed to failure. It must also be pointed out that the anatomical and other variations between individuals and of the position of the microphone on the throat would make a closer specification of a desirable characteristic of doubtful practical value.

The microphone should respond over as great a frequency range as possible, but it has been found in practice that good telephone communication can be obtained by the inclusion of frequencies up to from 3000 to 5000 cycles. The curve in Fig. 1 represents the performance of an actual apparatus including a microphone of the piezoelectric type as described below and in more

detail in my copending United States application Ser. No. 6,246, filed concurrently herewith.

From a broad point of view, the desired frequency characteristic shown in Fig. 1 applies to the entire system, including the device used to translate the electrical current back to sound. This frequency characteristic may be divided between several elements of the system as may be found economical or expedient. It may be, for example, incorporated solely in the microphone, or partly in other apparatus. It will usually be advantageous to obtain the frequency characteristic as near to the microphone as possible, in order to avoid the necessity of altering existing circuits into which the apparatus is to work. 15

A representative embodiment of this invention is shown in Fig. 2. This represents a complete telephone system of a simple type. Here the microphone 1 comprises a carbon-granule cell of conventional type which is provided with a button 2 which is driven by the vibration of the larynx. The microphone output is fed into the network L₁L₂, R₁R₂, C₁C₂ of the constant resistance type, then through transformer T₁, the line, and transformer T₂ to the telephone receiver 3. The condenser C₃ serves to confine the direct current from battery 4 to the microphone circuit. The desired frequency characteristic, shown in Fig. 1, is obtained by means of the network in combination with the mechano-electrical characteristic of the microphone. If the microphone is so designed as to have a constant output for a given displacement at all frequencies, its output voltage, for constant velocity excitation, will vary inversely as the first power of the frequency as 35 shown by curve B, Fig. 3. The network provides the rising transmission characteristic, curve C, and these transmission characteristics combine to provide the required characteristic, curve D.

The apparatus shown to the left of line ab of Fig. 2 may be replaced by the equipment illustrated in Fig. 4. The device 1' which converts the vibrations of the larynx into electrical voltages includes two units 4 that are applied symmetrically to the larynx and which, as shown, 45 are of the piezoelectric type such as described in my copending application. The units are wired in parallel so that their effects are additive electrically, and are shielded electrically by the metallic housing 5 and shielded cord 6, one terminal of each piezoelectric unit being grounded to the shield. 50

The output terminals of the microphone are connected to the input terminals of the first tube 7 of a two-stage amplifier. These input terminals 55 are shunted by a resistance R₁ which serves as a grid leak to fix the direct current bias on the grid G₁ of tube 7 and which has the further function of establishing a definite relation between the alternating current voltage applied to the grid and the voltage generated by the microphone, the relation being such that the input voltage rises with frequency. A part of the desired frequency characteristic of the whole system may thus be obtained at this portion of the circuit. This effect is obtained by selecting a value for resistance R₁ which is lower than the capacitive reactance of the piezoelectric crystals in the microphone at the higher frequencies. A relatively low value of resistance R₁ has other advantages in that it tends to minimize any variation in output due to leakage in the microphone crystals or the connecting cord. 65

The relation between the voltage across resistance R₁ and the voltage generated by the 75

microphone in a typical case is shown by the dotted line curve E of Fig. 5. The various frequency components of the electrical currents were generated from the mechanical vibrations of the body at conversion ratios that increased with frequency in the useful voice frequency range. The conditions under which this curve was obtained were as follows: the two crystals connected in parallel each had a capacity of .001 microfarad at 20° C., and resistance R_1 was 50,000 ohms.

The rising frequency characteristic of the microphone is supplemented by designing the amplifier, principally the first stage, to have a rising frequency characteristic, i. e. a gain that rises with frequency. The plate circuit of the pentode tube 7 of this stage includes the primary winding of the coupling transformer T_1 in parallel with a resistance R_3 , the reactance of the transformer being low compared with the resistance R_3 and plate resistance in parallel, thus providing a gain characteristic which rises with frequency. The transformer T_1 is in fact made resonant at a frequency near the upper limit of the desired frequency range. The frequency characteristic of the second stage, tube 8, is substantially flat. By shunting the output transformer T_2 with a resistance R_5 , the output impedance, viewed from the output terminals, may be made a substantially pure resistance at all frequencies. In this way, the microphone and associated amplifier may be adapted to replace the conventional carbon microphone of about 100 to 200 ohms resistance without affecting the frequency characteristics of other parts of the circuit.

To limit regeneration, the terminals of transformer T_1 , as shown, are reversed from their normal polarity. Grid biases for the two amplifier tubes are obtained from the voltage drop through the cathode resistances R_2 and R_4 , respectively. The condensers C_1 , C_2 , C_3 are the usual by-pass condensers to limit intercircuit coupling, resistances R_6 , R_7 are decoupling resistances in the plate circuits, and resistance R_8 is a so-called bleeder.

The overall frequency characteristic of the amplifier is shown by the curve F of Fig. 5 in which the ordinates represent the output voltage plotted against frequency for a fixed voltage applied across the resistance R_1 . The relation between the voltage output terminals of the amplifier and frequency, for a constant velocity excitation of the microphone, is shown by curve A of Fig. 1.

It is not always convenient mechanically to completely shield the microphone and in such cases, when the wearer of the microphone is in a radio frequency radiation field, some radio frequency energy may leak to the amplifier. Examples of such situations are found in open cockpit airplanes where the microphone may be used to modulate a radio transmitter. Such stray radio frequency voltages may be prevented from reaching the grid of the amplifier tube by a filter network such as shown in Fig. 6. The general form of the amplifier circuit may be substantially identical with that shown in Fig. 4, and certain elements of the Fig. 6 circuit are therefore identified by the corresponding reference characters of Fig. 4. The filter circuit for blocking the transmission of radio frequency voltages comprises the choke coil L and the shunt condenser C which are connected between the microphone terminals and the input terminals of the ampli-

It will be understood that there is considerable latitude in the choice or design of the different elements of the sound translating apparatus, and in the frequency response characteristics of the several elements. The desired frequency response characteristic of the complete system may be obtained in a variety of ways other than those herein described. In the Fig. 4 circuit, for example, the resistor R_1 could be made larger and the resulting reduction in the power of the response versus frequency relation can be compensated in the design of the microphone or the amplifier.

It will therefore be apparent that the invention is not restricted to the particular methods and embodiments herein described and that various changes which will occur to those familiar with this art fall within the scope of my invention as set forth in the following claims.

I claim:

1. Sound translating apparatus comprising a mechano-electric transducer substantially non-responsive to sound waves in air and actuated by the vibrations of the body due to the voice, and an electrical network for transmitting the electrical output of said transducer, said transducer and network having an overall frequency response characteristic which rises progressively with frequency from 200 to about 4000 cycles when the transducer is vibrated at constant velocity, whereby the electrical current output of said network may be converted into sound waves having an acoustical quality comparable to that of the voice.

2. Sound translating apparatus as claimed in claim 1, wherein said transducer has a frequency response characteristic which falls off with increasing frequency, and said network has a characteristic which rises with frequency at a rate which overcompensates the falling characteristic of said transducer.

3. Sound translating apparatus as claimed in claim 1, wherein both said transducer and said network have frequency response characteristics which rise with frequency.

4. Sound translating apparatus comprising a mechano-electric transducer substantially non-responsive to sound waves in air and actuated by the vibrations of the body due to the voice, and an electrical network for transmitting the electrical output of said transducer, said transducer and network having an overall frequency response characteristic which rises as a predetermined power of the frequency over the voice frequency range of from 200 to about 4000 cycles when the transducer is vibrated at constant velocity, whereby the electrical current output of said network may be converted into sound waves having an acoustical quality comparable to that of the voice.

5. Sound translating apparatus comprising a mechano-electric transducer substantially non-responsive to sound waves in air and actuated by the vibrations of the body due to the voice, and an electrical network for transmitting the electrical output of said transducer, said transducer and network having an overall frequency response characteristic which rises as a power of the frequency which is not less than unity over the useful voice frequency range of from 200 to about 4000 cycles when the transducer is vibrated at constant velocity, whereby the electrical current output of said network may be converted into sound waves having an acoustical quality comparable to that of the voice.

6. An electrical communication system com- 75

- prising a mechano-electrical transducer substantially non-responsive to sound waves in air and actuated by the mechanical vibrations of the body due to voice, a transmission circuit, and a sound reproducer, said system having an overall transmission efficiency which produces an output that rises progressively with frequency in the useful voice frequency range of from 200 to about 4000 cycles when the transducer is vibrated
- 5 at constant velocity, whereby the reproduced sound has an acoustical value simulating that of the voice.
7. An electrical communication system of the type including a mechano-electrical transducer substantially non-responsive to sound waves in air and actuated by mechanical vibration of the body due to the voice, a transmission circuit, and a sound reproducer, characterized by the fact that the system has an output which rises as a 15 power of the frequency over a substantial part of the useful voice frequency range of the system of from 200 to about 4000 cycles when the transducer is vibrated at constant velocity, whereby the reproduced sound has the acoustical quality
- 20 of the voice.
8. In sound translating apparatus, the combination with a throat microphone of the piezoelectric type, said microphone having a capacitive reactance over its frequency range of response, of a resistor shunted across the output terminals of said microphone, the resistor having a resistance less than the capacitive reactance of said microphone over the greater part of the said frequency range of response, whereby the relation between 25 the output voltage across the microphone terminals and voltage generated by the microphone rises with frequency.
9. In sound translating apparatus, the combination with a throat microphone of the piezoelectric type, said microphone having a capacitive reactance over its frequency range of response, a resistance shunted across the output terminals of the microphone, a vacuum tube and connections between the input terminals thereof 30 and the microphone terminals, and an impedance network cooperating with said tube to effect operation thereof as an amplifier, the overall transmission efficiency of said microphone and amplifier varying with frequency to produce a relation
- 35 between amplifier output voltage and the voltage

generated by the microphone which rises with frequency.

10. In sound translating apparatus, the combination with a throat microphone including a transducer unit, and a vacuum tube amplifier stage having output terminals; of means for developing across the output terminals of said amplifier stage an output voltage which rises with frequency when said microphone is vibrated at constant velocity, said means including an additional amplifier stage between said microphone and said first-mentioned amplifier stage, the additional amplifier stage having a rising frequency characteristic.

11. The invention as claimed in claim 10, wherein the additional amplifier stage includes a transformer resonating at a frequency near the upper limit of the range of frequencies to be transmitted thereby.

12. The invention as claimed in claim 10, in combination with a filter network between said microphone and the additional amplifier stage to prevent the application of radio frequency voltages to the additional amplifier stage.

13. The process of reproducing speech which comprises the steps of translating mechanical vibrations of the body due to the voice into electrical currents, selectively amplifying the several frequency components of the vibration-produced currents at gains which increase with the frequency of such components in the useful voice frequency range of from 200 to about 4000 cycles, transmitting the amplified electrical currents to a desired reproduction point, and converting the transmitted and amplified currents into sound waves.

14. The process of reproducing speech which includes the steps of selectively generating electrical currents from mechanical vibrations of the body due to the voice at conversion ratios that increase progressively with frequency in the useful voice range of from about 200 to about 4000 cycles, amplifying the resulting electrical currents at gains which increase progressively with frequency within the said useful voice range, transmitting the amplified electrical currents, and converting the transmitted and amplified currents into sound waves.

STUART BALLANTINE. 50
